UNITED STATES PATENT OFFICE.

HENRY H. CUTLER, OF THREE OAKS, MICHIGAN, ASSIGNOR TO THE WARREN FEATHER-BONE CO., OF THREE OAKS, MICHIGAN, A CORPORATION OF MICHIGAN.

LEGGING.

1,273,586.

Specification of Letters Patent.

Patented July 23, 1918.

Application filed April 26, 1918. Serial No. 230,955.

To all whom it may concern:

Be it known that I, HENRY H. CUTLER, a citizen of the United States, and a resident of Three Oaks, in the county of Berrien and State of Michigan, have invented certain new and useful Improvements in Leggings, of which the following is a specification.

My invention relates to leggings, particularly to military leggings, and its general object is to produce a more serviceable and efficient construction.

More in detail, the object is to provide improved flap stiffening construction and arrangement and improved supporting means for lace receiving attachments, the construction and arrangement being such that there will be a saving of material and reduction in weight, and the legging will be pliable yet sufficiently stiffened to prevent wrinkling, bulging, or buckling thereof.

In the construction of leggings the common practice has been to insert solid steel stiffening bars in the legging flaps, which bars are punched out to provide openings for receiving hooks, eyes, or other lace receiving attachments. Such metal bars add greatly to the weight and cost, and if made light enough to give sufficient pliability, are easily broken. I therefore provide built-up stiffening members for the flaps which will give the necessary stiffening support and pliability and to which hooks or eyes can readily be secured. Preferably these built-up stiffening structures comprise an outer frame of wire of suitable gage and temper, and a filler strip preferably in the form of "featherbone" to which hooks and eyes can be easily secured.

On the accompanying drawing—

Figure 1 is a side elevational view of a legging,

Fig. 2 is an enlarged sectional view on plane 2—2, Fig. 1,

Fig. 3 is an enlarged sectional view on plane 3—3, Fig. 1,

Fig. 4 is a perspective view of a wire stiffening frame, and

Fig. 5 is a perspective view of a filler strip for the stiffening frame.

5 represents the body of the legging and 6 and 7 the inner and outer flaps respectively. The outer flap 7 is hemmed along its edge to provide the longitudinal pocket 8 for a stiffening structure and on the in-

ner flap a short distance inwardly from its edge a strip 9 is sewed to form a longitudinally extending pocket 10 for the stiffening structure. My improved stiffening structure is clearly shown in Figs. 4 and 5. 60 A length of wire is bent to form the elongated frame 11 having parallel sides and rounded ends, the wire ends being preferably secured together as by welding, as indicated at 12. The wire frames are of a width 65 to snugly fit the pockets 8 and 10 and are of a length to extend substantially from the top to the bottom of the flap pockets. These frames, being of wire, are pliable and springy but are sufficiently stiff to keep the 70 legging in shape and to prevent sagging, buckling, or bulging thereof. Hooks and eyes are usually provided together with a lace or cord for tying the flaps together to secure the legging in place. Where these 75 hooks and eyes are applied merely to the fabric such as canvas, the strain thereon will tend to pull them out or tear the fabric. I therefore provide a filler for the wire frames, this filler being in the form of a 80 strip 13 to fit in the wire frames and flexible to assist the frames keeping the legging in shape, and also to serve as a support for the hooks and eyes. Preferably I employ what is known in the trade as "featherbone" 85 strip, formed by intimately binding slivers or fibers of turkey quills. Such strip is very light yet very elastic and strong, and can be readily punched to provide openings 14 for receiving hooks and eyes or other fastening 90 members. The filler strips are placed within the wire frames and then the stiffening structures thus formed are slipped into the pockets 8 and 10, the pockets being then snugly filled and the fillers held within the 95 frames. These stiffening structures are much stronger and more durable than solid steel stiffener strips and much lighter and cost considerably less.

The means shown for securing the legging 100 flaps together are hooks and eyes and a lace or cord, the hooks and eyes being applied to extend through the holes 14 of the filler strips and are then riveted rigidly in place. As shown, a hook 15 is provided at the lower 105 end of the inner flap to be opposed to the two eyes 16 and 17 near the lower end of the outer flap. Intermediate the legging ends the inner flap has the hook 18 and the outer flap the eyes 19 and 20. At the top, the in- 110

2
ner flap has the eye 21 and the outer flap the eye 22, an extra eye 23 being provided behind the stiffening section. The lace or cord 24 is slipped outwardly through the 5 lowest eye 16 and is anchored as by being knotted. It is then slipped inwardly through the eye 17 and then outwardly and inwardly through the eyes 19 and 20 respectively, the lace then forming the loops 10 25 and 26 for receiving the hooks 15 and 18 respectively. The upper end of the lace is inserted in suitable fashion through the upper eyes 21, 22 and 23 and after being drawn tight to bring the flaps together, a knot is tied therein. The filler strips 13 can of course be of other material which is light, flexible and strong, but I have found that "featherbone" is very desirable and efficient.

Having described my invention, I claim 20 as follows:

1. In a legging, a pocket extending lengthwise thereof, an elongated elastic wire frame fitting in said pocket, and a strip of flexible material forming a filler for said frame.
- 25 2. A stiffening structure or stay for wearing apparel comprising a flexible elongated wire frame, and a filler strip for said frame of flexible material.
3. A stiffening structure or stay for wear-

ing apparel consisting of a rectangular elongated wire frame, and a filler strip of "featherbone" for said frame.

4. In a legging, the combination with the flaps thereof, of pockets provided in said flaps, elongated wire frames inserted in said pockets, flexible filler material within said wire frames, said wire frames serving as stiffening members or stays for the legging, and lace receiving attachments secured to the legging fabric and to said filler material.

5. In a legging, the combination with the flaps, of pockets extending from top to bottom thereof, stiffening or stay structures inserted in said pockets, each stiffening structure comprising a flexible wire frame for engaging with the sides and ends of said pockets and a strip of "featherbone" within the wire frame, and lace receiving attachments secured to the flaps along the "featherbone" strips.

6. A stiffening structure or stay for wearing apparel consisting of an elongated rectangular wire frame, and a flexible filler of lighter flexible material.

In witness whereof, I hereunto subscribe my name this 22nd day of April, A. D. 1918.

HENRY H. CUTLER.
